SMOKING PIPE

Shalmy C. Oden, 1593 Jefferson, Muskegon, Mich.

Filed July 28, 1958, Ser. No. 51,976

Term of patent 14 years

(Cl. D85—8)

Fig. 1 is a side elevational view of a pipe, showing my new design;

Fig. 2 is a front elevational view; and

Fig. 3 is a perspective view thereof.

My design of a smoking pipe is characterized by an offset mouthpiece in relationship with an enlarged cylindrical body portion which is formed at the base of the bowl in the manner shown.

I claim:

The ornamental design for a smoking pipe, substantially as shown and described.
